UNITED STATES PATENT OFFICE

149,109

DESIGN FOR AN ELECTRIC SWITCH
HOUSING

Phillip A. Celander, Freeport, Ill., assignor to
First Industrial Corporation, Wilmington, Del.,
a corporation of Delaware

Application January 18, 1946, Serial No. 125,690

Term of patent 7 years

(Cl. D26—13)

To all whom it may concern:

Be it known that I, Phillip A. Celander, a citizen of the United States, residing at Freeport, in the county of Stephenson and State of Illinois, have invented a new, original, and ornamental Design for an Electric Switch Housing, of which the following is a specification, reference being had to the accompanying drawing forming part thereof.

In the drawing:

Figure 1 is a side elevational view of an electric switch housing showing my new design, the opposite side of the housing being a mirror image of Figure 1;

Fig. 2 is an elevational view of a side edge thereof;

Fig. 3 is a top view;

Fig. 4 is a side elevational view of the side opposite Fig. 2, and

Fig. 5 is a bottom view thereof.

The dominant features of the design reside in the portions shown in full lines.

I claim:

The ornamental design for an electric switch housing, substantially as shown and described.

PHILLIP A. CELANDER.
